UNITED STATES PATENT OFFICE.

WILLIAM F. POSTLES, OF PORTLAND, OREGON.

BRACKET-SUPPORT.

1,247,449.

Specification of Letters Patent. Patented Nov. 20, 1917.

Application filed September 22, 1915. Serial No. 52,055.

To all whom it may concern:

Be it known that I, WILLIAM F. POSTLES, a citizen of the United States, residing at Portland, in the county of Multnomah and State of Oregon, have invented certain new and useful Improvements in Bracket-Supports, of which the following is a specification.

My invention relates to bracket supports and more particularly to a combined embroidery rack and book support.

The primary object of my invention resides in the provision of an improved supporting means for removable association with the arm of a chair or other suitable support for holding an embroidery rack in various adjusted vertical and horizontal positions, said rack being incidentally removable to permit of the application of a book support which can be held in like manner, thereby providing a device for holding a rack in a convenient or any desired position to permit of embroidery being worked or to maintain a book or the like in a suitable position corresponding to the desire of the person who is using the device.

Another object of my invention resides in the improved means for connecting an embroidery rack to a support as well as novel means for obtaining a horizontal adjusted position of the rack or book support.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claims forming a part of this specification.

43 In the drawings:

Figure 1 is a side elevational view of my invention associated with the arm of a chair, the dotted lines illustrating the horizontal and vertical adjustments obtained;

50 Fig. 2 is a top plan view of the embroidery rack;

Fig. 3 is a transverse sectional view taken on the line 3—3 of Fig. 2 in the direction in which the arrow points, illustrating to 55 advantage the novel means for connecting the embroidery rack to the support, the dot-

ted lines illustrating an adjusted position of the rack;

Fig. 4 is a rear elevational view of a book support associated with the vertical adjusting rod; and

Fig. 5 is a side elevational view of the same.

Referring more particularly to the drawings in which similar reference numerals 65 designate like or corresponding parts throughout the different views, I provide my improved supporting means in this instance including a rod 1 having a head 2, the rod having rotatably mounted thereabout a sleeve 3. Arms 4 and 5 extend laterally from the sleeve 3 in spaced parallel relation to each other, the arm 5 being shorter and provided with an opening in which is mounted a clamping screw 6, said 75 screw being operable for removably maintaining the arm 4 in engagement with a chair arm 7 or like support. Rotatably associated with the rod is preferably a U-shaped supporting member generally designated 8, the arms 9 of which are journaled about the rod adjacent the vertex. A spacing sleeve 10 is arranged about the rod and between the arms 9 for facilitating the clamping of the U-shaped member in various positions through the medium of a set screw 11. The lower arm of the U-shaped member extends upwardly and has its terminal bent into parallelism with the upper arm. Both of the terminals of the member are 90 provided with openings, between which there is rotatably mounted the sleeved end of a horizontally extending rod 12, the mounting thereof being facilitated through the medium of an eye bolt 13, the lower end of 95 which adjustably engages the opening in the lower arm 9 whereby when tightened the arm will be removably held in various positions of adjustment. The outer end of this rod 12 is enlarged and provided with a vertical opening 14 and a horizontally extending opening 15 in the free end thereof which communicates with the vertical opening 14, the horizontal opening having a set screw 16 adjustably mounted therein for a purpose 105 to be hereinafter described.

The vertical adjusting means of the supporting bracket in this instance consists essentially of a rod 17 having an upper looped end 18 about which loop are arranged depending spaced ears 19 of the embroidery rack 20, the ears are provided with open-

ings which are adapted to aline, at times, with the opening in the loop so as to receive the thumb bolt 21, the latter being associated with a nut 22 for facilitating angular adjustment of the rack with respect to the rod 17. As is to be noted by adjusting the set screw 16, vertical adjustment of the rod 17 will be obtained.

The embroidery rack in this instance consists essentially of an annular band 23 provided on its outer periphery with a groove 24 in which is removably clamped the cloth that is to be embroidered through the medium of a ring 25. It is now thought to be understood that from this arrangement, after the clamping screw 6 has been adjusted on the chair by operating the clamping screw 11, desired horizontal adjustment of the support can be readily obtained. By adjusting the set screw 16 as previously stated, vertical adjustment can be obtained and finally by adjusting the thumb bolt 21 angular adjustment of the embroidery rack can be obtained.

If it is so desired a book support can be associated with the supporting arm 17 as is readily apparent upon reference to Figs. 4 and 5. The book support that has been provided for accomplishing this purpose consists of a rectangular plate 26 having a supporting flange 27 formed by bending the lower longitudinal edge at right angles to the main portion. Spaced ears 28 are carried by and projecting from the rear surface of the plate, said ears being provided with openings through which the thumb bolt 21 may be readily engaged and also engage the opening in the looped end of the rod 17 and be engaged by the nut 22.

Although I have shown and described the preferred embodiment of my invention, I desire to be understood that I am not to be limited to the exact details shown. However, I desire that great stress be laid upon the arrangement of the improved means for obtaining horizontal, vertical and angular adjustment of an embroidery rack in order that the work carried thereby can be conveniently placed before the user. Attention is also directed to the improved means for clamping the various arms and rods in adjusted positions.

From the above description taken in connection with the accompanying drawings, it can easily be seen that I have provided a device that is simple in construction, containing but a few simple parts that can be cheaply manufactured and assembled and

when assembled can be placed upon the market and sold at a minimum cost.

60

It will be understood that the above description and accompanying drawings comprehend only the preferred embodiment of my invention and that various minor changes in detail of construction, proportion and arrangement of the parts may be made within the scope of the appended claims and without sacrificing any of the advantages of my invention.

65

Having thus fully described my invention, what I claim as new and desire to secure by Letters Patent, is:—

70

1. A bracket including a vertical supporting rod, a clamp associated with the rod for removably holding the rod on a suitable support, a U-shaped supporting element pivotally mounted on the rod, a sleeve disposed about the rod and arranged between the arms of the supporting element, a fastening element mounted on the free end of the rod and co-operating with the sleeve for holding the supporting element in various adjusted positions laterally of the rod, a horizontal arm having the sleeved end thereof arranged between the free ends of the supporting element, an eye bolt passing through the upper arm and the sleeved end and threaded to adjustably engage the lower arm whereby to pivotally connect the horizontal arm between the arms of the supporting element and maintain the said horizontal arm in various positions of adjustment, and work holding means adjustably associated with the free end of the horizontal arm.

80

2. A bracket, comprising a clamp, that includes a tubular spacing and supporting portion, a U-shaped supporting element whose free ends lie in parallel planes, a rod passing through the element and the spacing and supporting portion of the clamp, a sleeve on the rod and placed between the arms of the supporting element, means to secure the rod and said element in a plurality of positions, said element being capable of movement in a horizontal plane, a horizontal arm pivotally mounted between the free ends of the U-shaped element, said mounting including an eye-bolt, and adjustably connected work holding means carried at the outer end of the horizontal arm.

85

In testimony whereof I affix my signature in presence of two witnesses.

WILLIAM F. POSTLES.
